UNITED STATES PATENT OFFICE.

ADAM EBERLE, OF CHICAGO, ILLINOIS, ASSIGNOR OF ONE-HALF TO GEORGE M. ILLINGWORTH, OF SAME PLACE.

GATE FOR ELEVATORS OR BRIDGES.

SPECIFICATION forming part of Letters Patent No. 438,991, dated October 21, 1890.

Application filed May 27, 1890. Serial No. 353,393. (No model.)

To all whom it may concern:

Be it known that I, ADAM EBERLE, a citizen of the United States, residing at Chicago, Illinois, have invented certain new and useful Improvements in Gates for Elevators or Bridges, of which the following is a specification.

My invention relates to the class of gates which are used as a guard against accident 10 at the elevator-shaft of warehouses or the approaches of bridges, but is especially to be used as an elevator-guard, which application I will more particularly describe; and the object of my invention is to provide a gate that shall be ornamental as well as substantial, and the working mechanisms of which shall be automatically operated to open or close the gates by certain mechanical devices upon the elevator-car, by which the conductor at will 15 may cause a gate to open upon the approach of the car to the floor upon which the aforesaid gate is situated, and also to close the gates after the car has passed said floor either in an upward or a downward course of its 20 travel.

Another feature of my improvement is that the operating parts are concealed beneath the flooring, and in consequence take up no valuable room and do not present an unsightly 25 appearance.

I have shown my improved gate as applied to guard against accident at the shaft of a freight-elevator; but the same construction may be applied to the approach of a drawbridge, as clearly shown in Figs. 5 and 6.

In the accompanying drawings, Figure 1 is a plan view showing the gate extended before the doorway of the elevator-shaft, the mechanisms for operating the gate, and the elevator-car in position to operate upon said mechanisms to cause the gate to be withdrawn from the doorway of the shaft. Fig. 2 is a side elevation of parts shown in Fig. 1, looking in the direction indicated by the arrow 2, Fig. 1. Fig. 3 is a central vertical section taken on line 3 3, Fig. 2, looking in the direction indicated by the arrow 3. Fig. 4 is a sectional detail of the operating appliance upon the elevator-car, the normal position being shown 45 in full lines, and the dotted lines indicate the position assumed when the passage of the car

is desired to cause the opening or closing of a gate. Fig. 5 is a plan view of a gate as applied to the approach of a draw-bridge. Fig. 6 is a sectional view taken on line 6 6 of 55 Fig. 5, looking in the direction indicated by the arrow 6.

In the accompanying drawings, A represents the floor-line.

B is a rail the upper surface of which is 60 upon the same horizontal plane as the floor. The rail B passes through the posts C at c, and posts C are provided with anti-friction rollers c'. A crossed cable D passes around the sheaves d d'. The strand passing over 65 sheave d is secured to one of the posts C, and the strand passing over sheave d' is secured to the other post.

E is a shaft, upon which is secured sheave d', which also carries one member of a pair of 70 miter-gears e, the other member being upon a shaft F, which also carries at its extreme ends gears f, whose teeth intermesh with the teeth of racks G, which racks travel in boxes G'. To the upper ends of racks G are pivotally secured linked rails H. The opposite ends of these rails are rigidly secured to the post C, said linked rails and racks furnishing the connecting means whereby posts C are returned to their closed position. Standards 75 80 h are provided with anti-friction rollers h', upon which the linked rails H rest. Studs I are provided with conical ends, that seat themselves in a concave recess in the ends of studs I', thus forming a rigid guard when 85 both members of the gate are in contact. Shaft E also carries one of a pair of miter-gears i, the other member being secured to an upright shaft J. At the extreme ends of shaft J are secured, respectively, one member of a pair of miter-gears J' J''. The fellow member of the miter-gear J' is secured to a short shaft j, that carries on its opposite end a gear j'. Shaft K likewise carries the fellow member of miter-gears J'' and gear k. Gears 90 95 k and j' are the initial point of operation of the mechanism for opening and closing the gate; but before describing the complete operation of the devices applied to the gate, it is necessary to describe the parts shown in 100 Fig. 4.

By referring to the aforesaid figures it will

be seen that a vertical rack L, secured to a movable block L', is secured in a way at the side of the floor of the elevator-car. Levers l' are pivotally secured to the car-floor, one 5 end of said levers being slotted, as at l', and receiving a pin l'' upon a bracket l''', said brackets being secured to the block L'. The opposite ends of levers l are secured to an operating-cable n, said cable passing beneath 10 the floor and to the opposite side of the car, and is then carried up over a sheave and applied to a foot-treadle T, as clearly shown in the drawings.

Midway of the block L' is secured the end 15 of a spring N, the opposite end of which is secured to the floor of the elevator-car and retains the block L' in its normal position.

In operation, supposing the car to be on its upward travel and the gate being closed, to 20 open the gate the conductor has but to press upon the foot-treadle before the floor of the car has passed the gear j', and through the action of levers l, caused by the retraction of cable n, block L' will be thrown out to a point 25 where the teeth of rack L will intermesh with the teeth of gear j', causing the rotation of shaft j until the rack L has passed the gear j'. The rotation of shaft j through the miter-gear connections transmits a rotary movement to 30 shaft J, which in turn rotates through miter-gears i shaft E, which carries sheave d', around which cable D is passed and secured to the posts of the gate, its opposite loop passing around sheave d and crossing itself mid- 35 way of its length. It is readily seen that the rotation of shaft E will cause the cable D to travel, as indicated by the arrow, and withdraw the gate-posts C. Miter-gears e transmit rotary motion to shaft F, which in turn 40 rotates the gears f, causing the racks G to be drawn downwardly, and carrying with them the linked rails H. To reverse the action of the gate, the car-floor having passed the gear j', the conductor will cause the rack L to engage 45 with the gear k, and through a reverse movement of the same parts just described the gate will be returned to its closed position.

A gate thus constructed may be made attractive, and at the same time very substantial, without a loss of valuable room. 50

I claim—

1. A gate or guard for elevator hatchways or bridges, provided with posts and secured to a crossed cable, and connecting parts and means for operating the cable to cause the 55 posts to approach toward or recede from each other, substantially as described.

2. A gate or guard for elevator hatchways or bridges, provided with posts having interlocking studs and secured to a crossed cable, 60 and connecting parts and means for operating the cable to cause said posts to travel upon a track in opposite directions, whereby to bar or clear the passage, substantially as described. 65

3. A gate or guard for elevator hatchways or bridges, provided with posts having interlocking studs and secured to a crossed cable, linked rails connected to said posts and adapted to be engaged by bars having operating- 70 racks, whereby to cause said posts to travel upon a track, substantially as shown and described.

4. A gate or guard for elevator hatchways or bridges, provided with posts having interlocking studs and secured to a crossed cable, 75 linked rails connected to said posts and adapted to be engaged by bars having operating-racks, whereby to cause said posts to travel upon a track, and mechanical devices applied 80 to an elevator-car, substantially as shown and described.

5. A gate or guard for elevator hatchways or bridges, provided with posts having interlocking studs and secured to a crossed cable, 85 linked rails connected to said posts and adapted to be engaged by bars having operating-racks, whereby to cause said posts to travel upon a track, and mechanical devices applied 90 to an elevator-car, substantially as described. 90

ADAM EBERLE.
